UNITED STATES PATENT OFFICE

AUGUSTUS C. DURDIN, JR., OF CHICAGO, ILLINOIS

DISPLACEMENT APPARATUS

Application filed August 2, 1926. Serial No. 126,496.

This invention relates to displacement apparatus of that type which employs a rotor in connection with water or other liquid for obtaining the pumping action. One of the objects of this invention is to minimize the centrifugal action of the rotor upon the water or other liquid so as to reduce vibration and wear. Another object is to simplify apparatus of this character, to increase its efficiency, to reduce the number of parts to a minimum and to otherwise improve upon the same. With these and other objects and advantages in view this invention consists in a displacement apparatus embodying a casing having alternately arranged liquid inlet passageways and intermediate fluid inlet passageways all arranged around a common centre, in combination with a rotor mounted in the casing and having a spirally arranged channel through which alternate slugs of said liquid, and intermediate slugs of said fluid are displaced by the action of the rotor. It further consists in an apparatus as above described having means for supplying liquid to the channel of the rotor. It further consists in an apparatus as above described in which the rotor is formed with a plurality of spirally arranged channels for receiving alternate slugs of liquid and intermediate slugs of fluid discharging them in alternate succession. It further consists in the several novel features of construction, arrangement and combination of parts hereinafter fully set forth and claimed.

The invention is clearly illustrated in the drawing accompanying this specification, in which:

Fig. 1 is a central, vertical section illustrating a simple embodiment of the present invention; Fig. 2 is an enlarged, detail, fragmental view of the rotor casing and rotor; Fig. 3 is a detail, vertical, cross section taken on the line 3-3 of Fig. 2; Fig. 4 is a detail, vertical, cross section taken on the line 4-4 of Fig. 2, and Fig. 5 is a detail, horizontal, section taken on the irregular line 5-5 of Fig. 4.

Referring to said drawing, which illustrates a simple embodiment of the invention, the rotor casing is seen at 10, and in the simple form of the invention illustrated in the draw-

ing, comprises a cylindrical casing having an end wall 11 at one end, and a discharge opening 12 at its other end. Within the casing is a rotor 13, which is mounted upon a drive shaft 14, journaled in a bearing 22 in the casing and arranged to be driven from any suitable source of power.

The rotor is formed with one or more channels 15 on its circumference, which channel or channels extend from one side of the rotor to the other, the end of each channel adjacent the end wall 11 of the casing being the inlet end to each channel and the other end of each channel being its discharge end. As a preference, said channel or channels are spirally arranged around the rotor and may be formed by blades or webs 16 that project out from the body 13^a of the rotor. Although the number of channels employed is immaterial to this invention broadly considered I have shown four in number, each channel extending through an arc of 180 degrees around the circumference of the rotor whereby each channel overlaps its adjacent ones. In the form of the rotor shown, the spaces between the adjacent ends of the adjacent blades or vanes comprise the inlet ends of the channels, and the spaces between the other ends of the blades or vanes comprise the discharge ends of the channels.

Between the end wall 11 of the casing and the rotor are alternately arranged liquid inlet passages 17 and intermediate fluid passages 20 all arranged around the axis of the drive shaft 14. The liquid passages 17 are formed between pairs of walls 18, which project outward from an annular wall 19, that surrounds the drive shaft. Said walls 18 extend from the casing wall 10 to the wall 19, and front wall 11 to the rotor, and divide the remainder of the space around the wall 19 into fluid passages 20. As a preference, the bearing bracket 21 for the drive shaft may have secured to it the sleeve portion 22 and said sleeve extends through the space 24 contained within annular wall 19. The annular wall 19 may be formed with a transverse or end wall 23, which joins with the end of the sleeve 22 to close one end of the annular space 24 between the wall 19 and

sleeve 22 and said space constitutes the main fluid inlet passage and runs to a fluid inlet opening 25 in which is secured the fluid inlet pipe 26. Ports 27 are formed in the annular wall 19, and connect the fluid inlet passage 24 with the several alternate air passages 20. The ends 28 of the air passages open directly to the inlet ends of the channels of the rotor and form the discharge ports from said fluid passages 20 to the inlet ends of the channels of the rotor, and the open ends 29 of the liquid passages 17 open directly to the inlet ends of said channels of the rotor and constitute the ports through which the liquid is delivered to said channels.

Means are provided for supplying the rotor with water or liquid and any suitable means may be provided for this purpose. For the purposes of illustration, I have illustrated a reservoir 30 for containing a body of liquid 31, which reservoir delivers liquid to the liquid passages 17 of the casing 10. To facilitate the circulation of the water, I have provided a transverse partition 32, which extends transversely of the reservoir and supports the rotor casing. Said partition separates the inlet side of the casing from the discharge side and permits air, gases or other elastic fluids to escape from the water or other liquid before the liquid again enters the rotor. When the apparatus is used as a vacuum pump the reservoir may be open to the atmosphere. If used as a compressor the reservoir is closed and a compressed air pipe may be connected thereto and run to any place where the compressed fluid is desired.

In the operation of this apparatus, liquid is supplied to the inlet end of the casing 10, either from the reservoir or from any other suitable source, and when the rotor is revolving, the inlet ends of the spiral channels pass the discharge ports of the liquid passages and intermediate fluid passages in alternate succession. The result is that as the inlet ends of each channel passes a liquid port, a slug of liquid enters the channel, and because of its inertia is not appreciably carried around by the channel, but is moved laterally across the rotor by the spiral blade. When said inlet end of the channel passes the next adjacent fluid port, fluid enters the channel in the space behind the slug of liquid and because of the partial vacuum which has been created behind the slug of liquid, as the inlet end of the channel reaches the next liquid port, a slug of liquid again enters the channel. The continued rotation of the rotor acts to discharge the liquid slugs and fluid slugs in succession as they reach the discharge ends of the channels, the elastic fluid bubbling up through the liquid in the reservoir and escaping. Each channel operates in the same manner taking in slugs of liquid and slugs of fluid and discharging them, and by pro-

viding a plurality of such channels upon the rotor, a very efficiently operating elastic fluid pump is obtained. The apparatus may be used as a vacuum pump, or as a compressor, and because of the fact that it can handle liquids as well as elastic fluids, it is very useful as a vacuum pump for removing air, gases and condensate from heating plants.

More or less variation of the exact details of construction is possible without departing from the spirit of this invention; I desire, therefore, not to limit myself to the exact form of the construction shown and described, but intend, in the following claims to point out all of the invention disclosed herein.

I claim as new, and desire to secure by Letters Patent:

1. The combination of a casing having a stationary cylindrical wall forming a cylindrical chamber, said casing having also liquid inlet ports and fluid inlet ports leading to said chamber, and a discharge opening leading from said chamber, and rotatory means within said chamber for causing alternative slugs of liquid and fluid to flow through said channel without imparting centrifugal force to said liquid and fluid slugs, said means including an open sided channel extending in a circumferential direction part way around the rotatory means, the open side of said channel being closed by said stationary cylindrical wall.

2. The combination of a casing having alternate liquid inlet ports and intermediate fluid inlet ports, all arranged around a common centre, said casing having a stationary cylindrical wall forming a cylindrical chamber and having a discharge opening, a rotor mounted to rotate in said cylindrical chamber between said inlet ports and discharge opening and having a spirally arranged open sided channel thereon, extending in a circumferential direction part way around the same and, containing an inlet end and a discharge end, said stationary cylindrical wall closing the open side of said channel and the inlet end of said spiral channel passing across the liquid inlet ports and fluid inlet ports in alternate succession, whereby slugs of liquid and slugs of fluid enter said channel in alternate succession and are discharged through said discharge opening, and a source of liquid supply for said rotor.

3. The combination of a casing having alternate liquid inlet ports and intermediate fluid inlet ports, all arranged around a common centre, said casing having a stationary cylindrical wall forming a cylindrical chamber and having a discharge opening, a rotor mounted to rotate in said cylindrical chamber between said inlet ports and discharge opening and having a plurality of overlapping spirally arranged open sided channels thereon, each extending in a circumferential

direction part way around the rotor and, each channel containing an inlet end and a discharge end, said stationary cylindrical wall closing the open side of said channels and the 5 inlet end of said spiral channel passing across the liquid inlet ports and fluid inlet ports in alternate succession whereby slugs of liquid and slugs of fluid enter said channel in alternate succession and are discharged 10 through said discharge opening, and a source of liquid supply for said rotor.

4. The combination of a casing having alternate liquid inlet ports and intermediate fluid inlet ports, all arranged around a common centre, said casing having a stationary cylindrical wall forming a cylindrical chamber and having a discharge opening, a rotor mounted to rotate in said cylindrical chamber between said inlet ports and discharge 20 opening and having a plurality of spirally arranged, overlapping blades extending in a circumferential direction part way around the circumference of said rotor and forming channels thereon, each open sided channel 25 containing an inlet end and a discharge end, stationary cylindrical wall closing the sides of said channels and the inlet end of said spiral channel passing across the liquid inlet ports and fluid inlet ports in alternate succession, whereby slugs of liquid and slugs of fluid enter and flow through said channel in alternate succession along lines substantially parallel with the axis of the rotor and are discharged through said discharge opening 30 with little circumferential action thereon, and a source of liquid supply for said rotor.

5. The combination of a casing having alternate liquid inlet ports and intermediate fluid inlet ports, all arranged around a common centre, said casing having a stationary cylindrical wall forming a cylindrical chamber and having a discharge opening, a rotor mounted to rotate in said cylindrical chamber between said inlet ports and discharge 40 opening and having a spirally arranged open sided channel thereon, extending in a circumferential direction part way around the rotor and, containing an inlet end and a discharge end, stationary cylindrical wall closing the 45 open side of said channel and the inlet end of said spiral channel passing across the liquid inlet ports and fluid inlet ports in alternate succession, whereby slugs of liquid and slugs of fluid enter said channel in alternate succession and are discharged through said discharge opening, a liquid supply reservoir opening to said liquid inlet ports and supplying liquid thereto.

6. The combination of a casing having alternate liquid inlet ports and intermediate fluid inlet ports, all arranged around a common centre, said casing having a stationary cylindrical wall forming a cylindrical chamber and having a discharge opening, a rotor 65 mounted to rotate in said cylindrical cham-

ber between said inlet ports and discharge opening and having a spirally arranged open sided channel thereon, containing an inlet end and a discharge end, said stationary cylindrical wall closing the open side of said channel and the inlet end of said spiral channel passing across the liquid inlet ports and fluid inlet ports in alternate succession, whereby slugs of liquid and slugs of fluid enter said channel in alternate succession and are discharged through said discharge opening, a liquid supply reservoir in which said casing is contained and in open communication with said liquid inlet ports and discharge opening. 70 75 80 85 90 95 100 105 110 115 120 125

7. The combination of a casing having alternate liquid inlet ports and intermediate fluid inlet ports, all arranged around a common centre, said casing having a stationary cylindrical wall forming a cylindrical chamber and having a discharge opening, a rotor mounted to rotate in said cylindrical chamber between said inlet ports and discharge opening and having a spirally arranged open sided channel thereon, containing an inlet end and a discharge end, said stationary cylindrical wall closing the open side of said channel and the inlet end of said spiral channel passing across the liquid inlet ports and fluid inlet ports in alternate succession, whereby slugs of liquid and slugs of fluid enter said channel in alternate succession and are discharged through said discharge opening, a liquid supply reservoir in which said casing is contained and in open communication with said liquid inlet ports and discharge opening, and a transverse partition in said reservoir around said casing separating the inlet side thereof from its discharge side.

8. The combination of a cylindrical casing having an inlet end, a tubular wall therein containing a fluid inlet passageway, walls extending from said tubular wall and dividing said inlet end of the casing into alternate liquid passages and intermediate fluid passages, all arranged around a common centre, and terminating in ports, there being fluid ports leading from said fluid inlet passageway to said fluid passages, and said casing having a stationary cylindrical wall forming a cylindrical chamber a rotor having a plurality of spirally arranged open sided channels extending circumferentially part way around the circumference of the rotor, said stationary cylindrical wall closing the sides of said channels, said rotor mounted to rotate being in said cylindrical chamber in a direction in which one end of the channels cross the ports of said liquid and fluid air passages and a source of liquid supply for said rotor.
